UNITED STATES PATENT OFFICE

MARTIN L. REED, OF WILSON, OKLAHOMA

COMBINATION THREAD PROTECTOR AND SUCKER ROD STRIPPER

Application filed November 5, 1930. Serial No. 493,670.

My present invention has reference to a new and novel device to be arranged upon the upper or outlet end of an oil well casing and which embodies elements or parts that will effectively wipe the sucker rod to strip the oil therefrom and to prevent the same from splashing over the rig floor, thereby keeping the floor clean and likewise saving oil, and for preventing the stripping or mutilation of the threads of the casing by affording a means for permitting the driving of the casing without contact with the threads thereof.

The primary object of the invention is the provision of a means for this purpose which shall be of a simple construction, easily and quickly applied and as readily removed from the outlet end or head of the casing and which shall be thoroughly efficient in practical use.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation illustrating the application of the improvement.

Figure 2 is a similar view looking at right angles to Figure 1.

Figure 3 is a sectional view approximately on the line 3—3 of Figure 1.

Figure 4 is a transverse sectional view approximately on the line 4—4 of Figure 3.

Figure 5 is a similar sectional view approximately on the line 5—5 of Figure 3.

Referring now to the drawings in detail the numeral 1 designates the upper tubular section of a well casing. Screwed on this section 1 there is the longitudinal branch of a T-coupling 2. To the lateral branch of

the T-coupling there is threaded the inner end of the discharge pipe 3. The T-coupling has its outer edges and its ends provided with the usual annular enlargements or hubs 4.

In carrying out my invention I arrange over the upper hub 4 of the longitudinal branch of the T-coupling the inner element of the improvement. This element comprises two substantially semi-cylindrical castings 5, respectively. The castings, adjacent their lower ends, are formed with internal notches 6 that receive therein the upper hub 4 of the T-coupling 2. The sections comprising the member 5 have at their confronting ends outstanding ears 7—7 and 8—8, respectively. The ears 7 are arranged vertically and the ears 8 are arranged horizontally. Preferably one of each pair of ears 7 and 8 is slotted and the other ear is provided with an opening. The opening in one of the ears 8 is threaded and there is received through the opening in the second ear 8 and screwed in the opening of the other ear a pivot bolt 9. A washer 10 is interposed between the ears 8 and through which washer the pivot bolt passes.

There is passed through the opening in one of the vertical ears 7 and received through the slot in the second ear 7 a bolt member 11 which is engaged by a nut 12. The nut when screwed home will bind the sections 5 around the T-coupling 2.

On the sides of the head member 5 at right angles with respect to the ears 7 and 8 there are downwardly directed hooks 13. The outer or cap member of the head, indicated by the numeral 14, also comprises two sections which are semi-cylindrical in plan and which are substantially cone-shaped in side elevation. Each of the sections 14 is centrally formed on its outer face with a depending lug 15 formed on its end with lateral extensions 16 to be received in the hooks 13. Adjacent to the confronting edges of the sections 14 and also arranged adjacent to the top of the said sections there are outstanding ears 17 and passing through these ears there are somewhat elongated bolts 18 engaged by nuts 19 to force washers 20 against the ears on one of the sections of the

member 14. A second washer 21 is forced against the ears on the second section 14 through the medium of helical springs 22 which surround the bolts and exert a pressure between the head of the said bolt 18 and the washer 21. From the above it will be noted that the sections comprising the outer or top members 14 of the head are removably connected to the lower section 5, and yieldably connected together by means which force the same toward each other and likewise the T-shaped lugs on the sections 14, engaging with the hooks 13 on the section 5 permit of a swinging of the outer head sections 14 on the inner head sections 5.

The substantially conical outer member 14 has the sections thereof, from its outer and reduced end formed with a substantially conical pocket 23 in which is seated a conical or cup-shaped compressible wiper member 24. The member, of course, comprises two sections, one being seated in the pocket of each of the sections of the top member 14 and the edges of the said wiper members project beyond the edges of the sections 14 and are held in the pocket by bolts 25 which are engaged by suitable nuts. The bolts pass through suitable openings in the sections 14 and are engaged by nuts whereby the rubber or like compressible washer members may be removed when worn and replaced by others.

The upper element of the sucker rod 26 passes through the round opening at the center of the compressible member 24 that provides the wiper element of the improvement.

With my improvement it will be noted that the sucker rod may be reciprocated and oil will be scraped therefrom by the compressible wiper or scraper element 24. A limited lateral movement of the upper section of the sucker rod is afforded by the yieldably connected sections that comprise the outer member 14. My construction may, of course, be successfully employed in connection with well boring systems as well as with pumps. When the outer cap member 14 is removed from the inner cap member the flat outer face of the inner member 5 serves as a means for protecting the threads on the T-coupling and the threads on the outer casing section, in which instance the T-coupling, with the improvement unscrewed from the casing section 1 illustrated by the drawings is screwed on another section which is attached to the said section 1.

It is thought the foregoing description when read in connection with the accompanying drawings will fully set forth the construction and advantages of my improvement to those skilled in the art so that further detailed description will not be required.

Having described the invention, I claim:

1. In a device for the purpose set forth, a well casing having a T-coupling in the outer

section thereof, an inner head comprising two sections which are adjustably connected and which are fixed on the outer end of the T-coupling, an outer head section which is removably and swingably secured to the inner head section and which also comprises two similar parts or sections, spring means for forcing the sections toward each other, adjusting means for said spring means and a compressible washer pocketed in the outer head section to engage with the sucker rod for the casing.

2. In a device for the purpose set forth, a well casing having a T-coupling screwed on the outer end thereof and the lateral branch of the T-coupling being connected with a discharge pipe, the ends of the coupling being formed with outstanding hubs, an inner head member having an annular groove to receive therein the outer hub, said head comprising two similar sections provided at their confronting ends with ears which are arranged at right angles with respect to each other, a pivot bolt passing through the horizontal ears, an adjusting bolt engaging the vertical ears, depending hooks on the sides of the inner head member at right angles to the ears, an outer substantially conical head member having T-shaped lugs on the sides thereof to be received in the hooks, the outer member comprising two sections, provided with ears adjacent to the confronting ends thereof, bolts passing through the ears, nuts engaging the bolts, washers on the bolts, with one pair of which the nuts contact, coiled springs between the heads of the bolts and the second pairs of washers, said outer head member having a substantially conical pocket therein, comprising two sections, whose ends project beyond the ends of the outer head member, a sectional compressible substantially cone-shaped wiper member seated in the pocket, removable means for holding the said member in the pocket, and the said wiper member having a central round opening through the top thereof whose walls contact with a sucker rod which is arranged in and passes through the casing and head.

In testimony whereof I affix my signature.

MARTIN L. REED.
